UNITED STATES PATENT OFFICE

CAMILO TALARIN, OF ROSARIO DE SANTA FE, ARGENTINA

INDICATING COPYHOLDER

Application filed October 4, 1929, Serial No. 397,343, and in Argentina August 17, 1929.

This invention refers to an improved copy holder provided with a device for indicating the line which is being copied, thus eliminating much of the trouble and annoyance caused by having to stop the work of copying and find the place or location of the particular line which is being copied.

Copy-holders of this class are known, but the present invention is provided with novel and useful devices for operating the sliding indicator bar.

In the accompanying drawings:

Fig. 1 is a front view of the copy holder,
Fig. 2 is a side view of the same, and
15 Fig. 3 is a detail section on the line 3—3 of
Fig. 1.

By reference to the said figures, it will be seen that the copy holder consists of an upright frame composed of the vertical members B and horizontal members B', mounted on a pedestal of suitable form, J. To the upper horizontal member B' there is attached by screws or rivets or the like, a spring or elastic clip A. All of the foregoing description applies to known devices.

On the right hand upright or vertical member of the frame, there is mounted a vertical rail upon which is dovetailed the sliding block M, to which there is hinged the indicator bar L, the left hand end of which extends entirely across the face of the copy-holder frame, and is movable vertically to indicate the line which it is desired to copy or read.

The said indicator bar L extends to the right for a short distance beyond the block M on which it is fulcrumed, forming a lever F by means of which the bar L may be lifted to introduce under it the paper or book, etc., which it is desired to read. About midway between the end of the lever F and the fulcrum block M, the shank of the lever F is fastened to the belt cord or elastic K which runs over the pulleys C and C' at the top and bottom respectively of the copy-holder frame. To one of the pulleys, preferably the lower one, C', there is attached by the shaft Q a button or handwheel D by which the pulley is revolved and the bar L made to move vertically to the desired position.

In order to introduce the copy below the indicator bar L, the latter is raised by pressing down the lever F; and as the latter is attached to the cord or elastic K at the point N, the said cord or elastic K acts as a spring 55 to return the bar L to its position on the frame.

Although the copy holder is especially designed as such, yet it will readily be seen that it is adaptable to any purpose which requires 60 the reading of a book or the like.

Having thus described my invention, what I claim and desire to protect by Letters Patent, is:

A copy holder including a frame, a sliding block on said frame, an indicating bar pivoted to said block, one end of said bar extending across the frame and the other end extending laterally from said block to form a lever end adapted to be depressed to move 70 the first mentioned end away from the frame to facilitate the introduction of a copy sheet under the bar, freely rotatable supporting pulleys, and a cord connected at one point to said bar for actuating the latter and normally retaining the bar in position upon the frame.

Signed at Buenos Aires, this sixth day of September, A. D. 1929.

CAMILO TALARIN.
